DESCRIPTION

(52) **U.S. Cl.** **D22/108**
USPC .....

FIG. 1 is a perspective view showing the top view, front view and left side view thereof;

(58) **Field of Classification Search**

FIG. 2 is a right side view thereof;

USPC D22/104, 108; 124/72, 74; 89/40.06,
89/41.19, 37.04, 33.04, 191.01, 200–204;
42/40, 41, 42.01, 42.02, 42.03, 43, 44,
42/45, 57, 69.01, 71.02, 72, 100

FIG. 3 is a left side view thereof;

See application file for complete search history.

FIG. 4 is a back view thereof;

(56) **References Cited**

FIG. 5 is a front view thereof;

U.S. PATENT DOCUMENTS

FIG. 6 is a top view thereof; and,

8,387,294 B2 * 3/2013 Bolden 42/1.01

FIG. 7 is a bottom view thereof.

Many aspects of the invention can be better understood with reference to the following drawings that include phantom lines, which do not form a portion of the claimed invention. For the drawings, the difference in stipple shading indicates a contrast of appearance and does not necessarily describe any color, texture, or material.
